UNITED STATES PATENT OFFICE.

JOSEPH A. WEBBER, OF VANCOUVER, WASHINGTON.

LOG-SPLITTING GUN.

Application filed October 28, 1924. Serial No. 746,429.

To all whom it may concern:

Be it known that I, JOSEPH A. WEBBER, a citizen of the United States, residing at Vancouver, in the county of Clarke and State of Washington, have invented certain new and useful Improvements in Log-Splitting Guns, of which the following is a specification, reference being had to the accompanying drawings.

This invention relates to means for splitting wood, and particularly to a wood splitting gun, that is a device adapted to contain an explosive charge, which device is adapted to be forced into the wood before the charge is exploded and then the charge exploded to split the wood.

In the timbered portions of this country, and in fact wherever wood is being worked up into products, particularly cord wood, the splitting involves considerable labor and in some cases where the wood is of a particularly tough kind, splitting by means of wedges becomes practically impossible. Many efforts have been made to split wood, particularly the larger logs, with explosive. This has been done by boring into the log and tamping a charge of powder into the hole. This method, however, is very unsatisfactory because of the amount of labor involved in boring the hole in the wood, placing the charge, and further on account of the fact that very often a mere piece of the wood will be blown off without doing the required splitting. Guns have been devised for the purpose, none of which have been successful, however, for one reason because the gun would be liable to break or be shattered at the same time as the log was shattered.

The object of this invention is to provide a gun, as it may be termed, of a very simple character, which is so constructed that it may be driven into the log in the same manner as a wedge is driven into a log, the gun being of sufficiently hard steel so that it will withstand the driving action and penetrate the hardest wood, this gun being hollow and containing a charge and having means whereby the charge may be fired.

A further object is to provide a gun of this character which is so constructed that the wood into which the gun is driven will form the wadding which closes up the mouth of the explosion chamber, the explosion of the charge driving this wadding forward, as it might be termed, and blowing the log

to pieces, the outside of the gun being supported during the explosion by the tension of the wood into which the gun is driven.

A still further object is to apply this same principle to a gun to be used for splitting slabs from logs.

Other objects will appear in the course of the following description.

My invention is illustrated in the accompanying drawings, wherein:

Figure 1 is a side elevation of a log splitting gun constructed in accordance with my invention;

Figure 2 is a section on the line 2—2 of

Figure 1;

Figure 3 is a section on the line 3—3 of Figure 2;

Figure 4 is a longitudinal section of the forward or magazine end of the slabbing gun;

Referring to these drawings, it will be seen that my log splitting gun comprises a cylindrical body 10 which is tapered, as at 11, at one end and which is formed with a longitudinally extending bore 12 extending inward from the tapered end and a counterbore 13 extending longitudinally from the inner end of the main bore 12, and that there is a fuse hole 14 extending inward from the side of the body and having a reduced extension 15 extending from this main fuse hole 14 into the reduced chamber 13. It will be seen that beyond the chamber 13 there is provided a driving head of solid metal.

In the use of this device, the gun is driven into the wood nearly as far as the fuse hole 14, the magazine formed by the bore and counterbore 12 and 13 being charged with powder or other explosive. As the gun is forced inward into the wood, the tapered extremity will wedge the fibers of the wood apart and the tapered extremity will act like a punch, punching a round core *a* out of the log *A*, this round core acting as a wadding. The powder or other explosive is preferably contained within the magazine or chamber 13. The wadding will extend up into the chamber 12 to an extent depending upon the degree to which the gun is forced into the wood. Upon the explosion of the charge, the wadding is forced out and the log is split, the tension of the wood which grips the wedge very tightly acting to prevent the wedge being forced out.

I have by continued experiments established a certain standard of size and

strength and proportions which permit the instrument to be particularly effective in actual practice. The standard size of this device will be eighteen inches long and preferably the gun will be made of a bar of chrome nickel steel and the gun will be one and five-eighths inches in diameter. The hole in the bore 12 will be eleven-sixteenths inches in diameter and drilled inward seven inches deep and from this will extend the smaller bore 13 which will be nine-sixteenths inches in diameter and drilled inward two inches. The fuse hole 14 is three-sixteenths inches and drilled in one-eighth of an inch into the steel with a smaller hole extending from the end of the main hole into the magazine 13. The tapered portion of the gun is four inches in length with the proportions above given and tapered from the full size 20 of the steel down to seven-eighths of an inch. For larger and heavier explosions the gun will be made eighteen inches in length and two and a half inches cross sectional diameter. The bore 12 will be nine inches deep 25 and one inch in diameter and the tapered magazine will be three inches deep and three-quarters of an inch in diameter. The point taper will be four and a half inches and tapered from the full size of the steel 30 two and a half inches to one and one-eighth inches. A smaller size than eighteen inches long and one and five-eighths inches diameter may be used for splitting small sticks such as ordinarily sixteen-inch wood. The charge may be ignited either with a fuse, 35 a battery, or a hot point.

In Figure 4 I show a modification of my invention forming what may be termed a slabbing gun, which is exactly the same as the form illustrated except that about one-half of the tapered portion 11 is cut away, as at 16, so that the explosion escapes in one direction or laterally and throws the slab off the stick.

I regard the proportions above given as being particularly important, inasmuch as I have only arrived at these proportions by continued experiments. At the same time, obviously, I do not wish to be limited to these exact proportions as these might be changed within small limits without departing from the spirit of the invention as defined in the appended claims.

I claim:

1. A wood splitting gun comprising a body of hard steel tapered at one end whereby it may be driven into a log, the body being formed with a longitudinally extending bore extending approximately half the length of the body and designed to contain

a charge and the body having an ignition opening extending laterally into the bore from the exterior of the body.

2. A wood splitting gun comprising a body of hard steel tapered at one end whereby it may be driven into a log, the body being formed with a longitudinally extending bore extending approximately half the length of the body and designed to contain a charge, the body having means whereby the charge within the bore may be ignited.

3. A wood splitting gun of the character described comprising a body of hard steel cylindrical in cross section and uniformly tapered toward one end, the body having a bore extending longitudinally of the body from said tapered end whereby the body may be driven into the wood to be split, and an extension from the inner end of the bore longitudinally of the body smaller in diameter than the bore and constituting a charge chamber, there being a fuse opening extending inward from the surface of the body into said discharge chamber.

4. A wood splitting gun of the character described comprising a cylindrical body tapered uniformly toward one end from a point intermediate the ends of the body, the body being formed with a longitudinally extending bore extending inward from said tapered ends, and a counterbore constituting an explosion chamber, the bore and counterbore together extending approximately half way of the body whereby the remainder of the body constitutes a driving head, there being a fuse opening extending radially inward from the surface of the body into the explosion chamber.

5. A wood splitting gun of the character described comprising a cylindrical body tapered uniformly toward one end from a point intermediate the ends of the body, the body being formed with a longitudinally extending bore extending inward from said tapered ends, and a counterbore constituting an explosion chamber, the bore and counterbore together extending approximately half way of the body whereby the remainder of the body constitutes a driving head, there being a fuse opening extending radially inward from the surface of the body into the explosion chamber, the tapered portion of the body being cut away for half the length of the tapered portion on one face so as to cause a lateral opening from the bore.

In testimony whereof I hereunto affix my signature.

JOSEPH A. WEBBER.
